United States Patent

Des. 236,201
Patented Aug. 5, 1975

236,201

DOOR

Ted Shoush, Independence, Mo., assignor to Ted Shoush Company, Inc., Independence, Mo.

Filed May 14, 1973, Ser. No. 360,109

Term of patent 14 years

Int. Cl. D25—02

U.S. Cl. D13—1 M

Fig. 1.

Fig. 2.

FIG. 1 is a front elevational view of a door; and FIG. 2 is a front perspective view thereof.

The rear of the door is plain except for the rear surface of the grille that is visible.

I claim:

The ornamental design for a door, as shown and described.
